ELLIOTT ALLINGHAM, OF TORONTO, ONTARIO, CANADA.

SLIP CONNECTION FOR DENTAL BRIDGework.

1,271,531.

Specification of Letters Patent.

Patented July 9, 1918.

Application filed March 30, 1918. Serial No. 225,740.

To all whom it may concern:

Be it known that I, ELLIOTT ALLINGHAM, dental mechanic, of the city of Toronto, in the county of York, in the Province of Ontario, Canada, have invented certain new and useful Improvements in Slip Connections for Dental Bridgework, of which the following is a specification.

My invention relates to improvements in slip connections for dental bridge work, and the object of the invention is to devise a slip connection whereby the removable bridge may be readily attached to the adjacent tooth or teeth and it consists essentially of a crown designed to be secured on the tooth and having a centrally grooved guide-way attached thereto, and adjacent guide-ways at each side of said grooved guide-way and a bridge having a tongue designed to fit into the central tongue of the crown and laterally extending tongues designed to fit into the grooves on each side of the central guide-way of the crown, the parts being arranged and constructed in detail as hereinafter more particularly explained.

Figure 1 is a perspective view showing my bridge attached to the crown.

Fig. 2, is a view from another point.

Fig. 3, is an enlarged detail showing the connection between the crown and the end of the bridge.

Fig. 4 is a perspective detail of the end of the bridge showing the crown removed.

Fig. 5, is a detail of the crown showing the guide-ways.

Fig. 6, is a longitudinal sectional view showing the connection between the crown and the bridge.

Fig. 7, is a sectional plan showing the connection between the crown and the bridge.

Fig. 8, is a detail of the guide-ways attached to the crown.

Fig. 9, is a detail of the tongues attached to the bridge.

45 In the drawings like characters of reference indicate corresponding parts in the various figures.

1 is the crown and 2 the bridge, which may be of any suitable form provided with 50 teeth 2' and the base which is adapted to fit the gum. The crown 1 is generally

formed of gold and is provided with a grooved guide-way 3 having lateral projections 4, which form guiding grooves 5 at each side of the guide-way 3. The base of 55 the bridge 2' is molded or formed up around a stem 6, which extends into the base as indicated in Figs. 6 and 7, and is turned up at the end into a vertical portion 6' forming a tongue.

60 The stem 6 is also provided with a bar 6² formed at the end into loops 6³, which end in inwardly extending lateral tongues 6⁴.

65 The crown, of course, is secured in the usual manner on the tooth to which the bridge is to be connected and the tongue 6' with the lateral tongues 6⁴ attached to the bridge 2 are pushed downward into the guiding grooves 3 and 5, which they fit closely and snugly when the bottom end of 70 the tongue comes opposite the bottom of the guide-way 3.

75 Such a slip connection as I describe enables the bridge to be readily inserted in position and not only this but the bridge just as readily removed, so that it may be cleaned.

80 The triple tongue formed by the central tongues and side tongues fitting into the central guiding groove and side guiding grooves 5 form a very rigid connection, and thereby maintain the bridge securely from lateral displacement and any rocking movement, which would make the bridge uncomfortable.

85 Although I show my slip connection only attached to one end of the bridge it will, of course, be understood that it may be with equal facility applied to a bridge extending between two crowned teeth, and thereby having the attachment at both ends of the bridge and on both crowns.

90 What I claim as my invention is.

95 1. In a slip connection for dental bridge work, the combination with a crown having a vertical guide-way held thereon, and adjacent guide-ways on each side of the main guide-way, of a bridge having a vertical end tongue and laterally extending tongues one on each side designed to slip into and 100 snugly fit the guide-ways in the crown.

2. The combination with a crown having

a guide-way formed in the center of the side and laterally projecting wings forming supplemental adjacent guide-ways, of a bridge having a stem provided with a vertical end portion and a bar on the inside of such end portion provided with bent ends forming a loop, the ends of which form lat-

eral extending tongues, the said tongues being adapted to fit into the guide-ways on the crown.

ELLIOTT ALLINGHAM.
